UNITED STATES PATENT OFFICE.

LEO J. GRUBMAN, OF BELLE HARBOR, NEW YORK, ASSIGNOR TO VOICES, INCORPORATED, OF NEWARK, NEW JERSEY, A CORPORATION OF DELAWARE.

SOUNDING REED.

Application filed May 9, 1925. Serial No. 29,005.

This invention relates to sounding reeds, and has for its primary object to provide a reed construction for "criers", "voices", and other sound producing devices such as are used in connection with dolls or other toys and the several parts of which are so constructed and relatively associated as to retain the vibratory sound producing element in accurate alignment with the sound channel or passage.

It is another object of my invention to provide a sounding reed wherein the use of cement, adhesives, binders or other fastening means to secure the several parts in fixed relation is dispensed with while at the same time the vibratory sound producing element will be positively secured and retained in its operative position with relation to the walls of the sound channel or passage so that it will at all times function in a positive and reliable manner.

To the above end, the essential features of my present improvements in one embodiment thereof consist in the provision of a sound passage or channel formed in a wall structure and opening at one of its ends upon one side of the wall for the egress of sound therefrom together with a vibratory sound producing element positioned in a recess or seat formed in the opposite side face of said wall and surrounding the open side of said channel and a retaining member for said element engaged upon one end thereof to fix said element in aligned relation with the channel, said retaining member having a part resiliently bearing on the sound producing element and said element having a vibratory tongue projecting beyond said part and overlying the ingress end of the sound channel or passage.

It is a further general object of my invention to provide a sounding reed, the several parts of which may be inexpensively produced by simple mechanical stamping operations and then expeditiously assembled into proper cooperative relationship.

With the above and other objects in view, the invention consists in the improved sounding reed, and in the form, construction and relative arrangement of the several parts thereof, as will be hereinafter more

fully described, illustrated in the accompanying drawings, and subsequently incorporated in the subjoined claims.

In the drawings wherein I have illustrated one simple and practical embodiment of my improvements, and in which similar reference characters designate corresponding parts throughout the several views,

Figure 1 is a longitudinal section through a sound producing device or crier illustrating one application of my present invention;

Fig. 2 is a horizontal section taken on the line 2—2 of Fig. 1;

Fig. 3 is a plan view of a wall provided with my improved sounding reed;

Fig. 4 is a longitudinal section taken on the line 4—4 of Fig. 3;

Fig. 5 is a transverse section taken on the line 5—5 of Fig. 3;

Fig. 6 is a fragmentary plan view similar to Fig. 3, the vibratory sound producing element and its retaining member being omitted;

Fig. 7 is a detail plan view of the sound producing element, and

Fig. 8 is a similar view of the retaining member.

For the purpose of illustrating one application of my present improvements, I have illustrated in the accompanying drawing, a well known type of sound producing device or crier such as is used in dolls, but it will become apparent as this description proceeds that in so far as the new reed construction is concerned, it is applicable to various other devices differently constructed and designed for other purposes or uses. As shown in Fig. 1, the sound producing means is enclosed within a tubular casing or shell 5 having suitably formed heads 6 and 7 respectively applied to its opposite ends and the head 7 being perforated for the escape of sound therethrough. To the opposite end of the casing wall 5 one end of a tubular flexible bellows wall 8 is suitably fixed, the other end of said tubular wall being provided with a weighty gravity movable head. As herein shown, this head consists of an outer cup-shaped member 9 of heavy metal, and the end of the tubular bellows wall is frictionally clamped against the

inner face of the marginal wall of this member by a flanged disc or wall 10 which is inserted within said end of the tubular bellows wall and then forced under pressure within the member 9. This latter member is provided with one or more openings such as that indicated at 11 whereby sound may freely escape from the space between said member and the wall 10 into the casing or shell 5 and finally pass through the escape openings in the casing head 7.

In the illustrated construction, my improved sounding reed is provided on the wall 10 of the weighty bellows head. As herein shown, a part of this wall indicated at 12 is die stamped or forced under pressure out of the plane of said wall to provide a channel or passage 13, the channel wall 12 at one of its ends being spaced from the wall 10, at which point an opening 14 is formed in the latter wall, thereby providing for the free and unrestricted egress of sound from said end of the channel. As clearly shown in Fig. 6 of the drawings, the side walls of the channel 13 extend in parallel relation from the opening 14. At the open side of said channel the face of the wall 10 is formed with a recess or seat 15 surrounding said channel. The opposite walls of this recess converge towards each other from the egress end of said channel to the opposite end thereof so that said recess is of the longitudinally tapering form as illustrated in Fig. 6 of the drawings.

Within the recess 15 and over the open side of the channel 13 the sound producing element 16 is adapted to be positioned. This element consists of a thin metal strip having a relatively wide portion 17 conforming in shape to the wider end portion of the recess 15 and adapted to fit snugly therein. The portion 17 of said element at its narrower end is provided with the relatively narrow longitudinally projecting tongue 18, the opposite side edges of which extend in parallel relation with each other. This tongue is of slightly greater width than the width of the channel 13 so that it overlies the opposite side edges of said channel. At this end of the channel 13, the base wall of the recess 15 is curved away from the inner face of the wall 10 as indicated at 19, thereby increasing the depth of this end of the recess 15. Thus, the tongue 18 of the sound producing element occupying the normal position shown in Fig. 4 of the drawings, is spaced from the curved section 19 of the base wall of the recess 15 and may, therefore, have free and unrestricted vibration in said recess over the ingress end to the channel 13.

After the sound producing element has been fitted within the recess 15, a retaining member or pad 20 is also fitted in said recess over and upon the wider portion 17 of said element. This retaining member may be

conveniently stamped from a thin sheet of fiber or other material and is of such dimensions that when it is forced longitudinally against the wider end wall of the recess 15, the edges of said member have a frictional wedging coaction with the edges of said recess, thereby securely locking said retaining member within the recess upon the sound producing element. This retaining member 20 at its narrower end terminates in a tapered section 21, which it will be observed, is free from frictional binding contact with the side walls of the recess 15. This end portion of the retaining member 20 therefore exerts a yielding resilient pressure upon the intermediate portion of the sound producing element 16 which is of corresponding shape and connects the parts 17 and 18 thereof with each other. It will be evident that since the part 17 of the sound producing element 16 fits snugly within the wider end of the recess or seat 15 and abuts closely at its side and end edges against the corresponding edges of said seat, that said sound producing element will be held against any possibility of longitudinal shifting movement in either direction or of transverse shifting movement in said recess so that the vibratory tongue 18 of said element will at all times remain in accurate alignment with the sound channel or passage 13. This is of particular importance in the proper production of the sound, since if this vibratory tongue became displaced so as to permit of the leakage of air between either side edge of the channel and the tongue without impingement upon said tongue, a more or less discordant noise would result. Therefore, it will be understood that the essential and fundamental feature of my present improvements resides in initially producing and thereafter maintaining an absolutely accurate alignment of the vibratory tongue with respect to the ingress end of the sound receiving channel or passage. While I preferably secure this sound producing element in place by the frictional interlocking engagement of the superposed pad or retaining member 20 with the walls of the recess or seat 15, any other or additional fastening or securing means may be employed for permanently fixing the vibratory sound producing element with relation to the reed channel.

From the above description, the construction of my improved sounding reed and the manner of assembling its several parts will be clearly understood. Assuming that the reed is applied to a device of the construction as shown in Fig. 1, in the gravity descent of the weighty bellows head, air will of course, be expelled under pressure from the bellows chamber bounded by the flexible wall 8 and forced through the channel 13. As the air enters the ingress end of this channel,

the free tongue 18 of the sound producing element 16 is caused to rapidly vibrate, thereby producing sound, such sound waves passing freely through the channel and being emitted from the egress end thereof. Owing to the form of the sound producing element and the resilient coaction of the end 21 of the retaining pad 20 therewith, the tongue 18 may have a maximum amplitude of vibratory movement without liability of distortion or permanent change in its normal relationship to the ingress end of the sound channel or passage. Heretofore it has been necessary to provide a binding, cement, or other means for fixing the vibratory sound producing element with relation to the reed channel. The reed as a separate unitary device, was then mounted or arranged in its operative position through an opening formed in the wall. It will be seen that I produce the sound channel or passage of the reed directly in the wall structure and provide a very simple and novel means for mounting the sound producing element and fixing the same in relation to the open side of said channel which does not involve the application or use of adhesives or other binding or fastening elements than the retaining member 20 which also possesses the additional function of yieldingly resisting excessive vibratory movement of the tongue 18. It will be appreciated that this retaining member can be very easily and quickly inserted in place and frictionally locked within the end of the recess 15 in the manner above explained. Therefore, the quantity production of such criers or sound producing devices may be greatly expedited by means of my present improvements.

While I have herein shown and described one practical embodiment of the device which I have found to be very efficient and satisfactory in its operation in actual practice, it will nevertheless be understood that the essential features of my improvements may also be embodied in various other alternative structures, and I accordingly reserve the privilege of adopting all such legitimate changes in the form, construction and relative arrangement of the several parts as may be fairly incorporated within the spirit and scope of the invention as claimed.

I claim:

1. In a sounding reed, a wall having a channel therein open at one end for the egress of sound, a sound producing element overlying the open side of said channel and having a vibratory tongue at one end impeding the ingress of air to the other end of said channel, and a retaining member for said element extending longitudinally thereon, said wall having means coacting with said retaining member to positively lock said member against longitudinal displacement relative to said tongue.

2. In a sounding reed, a wall having a channel therein open at one end for the egress of sound and also provided with a recess surrounding said channel at the open side thereof, a sound producing element having a part seated upon the base wall of said recess and provided with a free vibratory tongue projecting longitudinally from said part and overlying the other end of said channel to impede the ingress of air thereto, and a retaining member engaged upon said first named part of the sound producing element and frictionally coacting with the walls of said recess and held thereby against displacement relative to said tongue.

3. In a sounding reed, a wall having a channel therein open at one end for the egress of sound and also provided with a recess surrounding the open side of said channel and having its side walls converging towards each other from the egress end of the channel to the opposite end thereof, a sound producing element positioned in said recess and having a vibratory tongue overlying the latter end of the channel and impeding the ingress of air thereto, and a retaining member engaged upon said sound producing element and frictionally coacting with the side walls of said recess to secure said element against bodily displacement relative to said channel.

4. In a sounding reed, a wall having a channel therein open at one end for the egress of sound and also provided with a recess surrounding the open side of said channel and having its side walls converging towards each other from the egress end of the channel to the opposite end thereof, a sound producing element positioned in said recess and having a vibratory tongue overlying the latter end of the channel and impeding the ingress of air thereto, and a tapering retaining member adapted to be engaged upon said sound producing element and moved longitudinally thereof into frictional engagement with the side walls of said recess to secure said sound producing element against bodily displacement relative to said channel.

5. In a sounding reed, a wall having a channel therein open at one end for the egress of sound and also provided with a recess surrounding the open side of said channel and having its side walls converging towards each other from the egress end of the channel to the opposite end thereof, a sound producing element positioned in said recess and having a vibratory tongue overlying the latter end of the channel and impeding the ingress of air thereto, and a tapering retaining member adapted to be engaged upon said sound producing element and moved longitudinally thereof into frictional engagement with the side walls of said recess to secure said sound producing

element against bodily displacement relative to said channel, and said member having a reduced end portion spaced from the side walls of the recess and exerting a resilient bearing pressure upon said sound producing element adjacent to the vibratory tongue thereof.

6. In a sounding reed, a wall having a channel therein open at one end for the 10 egress of sound and a recess surrounding the open side of said channel and having its side walls converging towards each other from the egress end of the channel to the opposite end thereof, a sound producing element having a relatively wide longitudinally 15 tapering portion adapted to be engaged upon the base wall of said recess and frictionally coacting at its side edges with the converging side walls of the recess, said element 20 having a relatively narrow vibratory tongue projecting from said tapered portion thereof and overlying said channel to impede the ingress of air thereto, and a retaining member corresponding in form to the tapered 25 portion of said sound producing element and adapted to be engaged thereon and moved longitudinally thereof into frictional binding engagement with the side walls of said recess to secure said sound producing element 30 against displacement relative to said channel.

7. In a sounding reed, a wall having a channel therein open at one end for the 35 egress of sound and said wall provided with a recess surrounding said channel at the open side thereof, and a sound producing element adapted to be fitted within said recess and having a part interlocking with the walls of the recess to prevent longitudinal 40 shifting movement of said element relative to said channel, and said element also having a free vibratory sound producing tongue

overlying the other end of said channel to impede the ingress of air thereto.

8. In a sounding reed, a wall having a 45 channel therein open at one end for the egress of sound and provided with a recess surrounding said channel throughout its length at the open side thereof, and a sound producing element adapted to be fitted 50 within said recess and having a part interlocking with the walls of the recess to prevent longitudinal shifting movement of said element relative to said channel, and said element being wholly positioned in the 55 plane of said wall and having a free vibratory sound producing tongue overlying the other end of said channel to impede the ingress of air thereto, and additional means for permanently fixing said sound producing 60 element within said recess.

9. In a sounding reed, a wall having a channel therein open at one end for the egress of sound and also provided with a recess surrounding the open side of said 65 channel and having its walls converging towards each other from the egress end of the channel to the opposite end thereof, a sound producing element positioned in said recess and having a part overlying the egress 70 end of the channel and abutting snugly against the wider end edge and the side edges of said recess to prevent longitudinal or transverse shifting movement of said sound producing element in said recess, and 75 said element having a relatively narrow vibratory tongue spaced from the walls of the recess and overlying the other end of said channel to impede the ingress of air thereto.

In testimony that I claim the foregoing 80 as my invention, I have signed my name hereto.

LEO J. GRUBMAN.
